UNITED STATES PATENT OFFICE.

ADOLF FREUDENBERG, OF ELBERFELD, GERMANY.

SINGLE-THREAD LACE-BRAIDING MACHINE.

Application filed August 30, 1921. Serial No. 497,076.

(GRANTED UNDER THE PROVISIONS OF THE ACT OF MARCH 3, 1921. 41 STAT. L., 1313.)

To all whom it may concern:

Be it known that I, ADOLF FREUDENBERG, a citizen of the German Empire, residing at Elberfeld, 43 Ronsdorferstrasse, Germany, have invented certain new and useful Improvements in Single-Thread Lace-Braiding Machines, for which applications have been filed in Germany, December 17th, 1919, under Serial Numbers K. 71,328 VII/25b and K. 71,329 VII/25b and April 9, 1920, under Ser. No. K. 72,635 VII/25b; England, September 9, 1920, Patent 174,674, and October 30, 1920, Patent 161,552; Holland, March 24, 1921, application 18,628, and 15 March 29, 1921, application 18,786; Czechoslovakia, March 29, 1921, application P. 2,307/21; France, March 29, 1921, Patent 533,369, and March 30, 1921, patent of addition 24,560 to the aforesaid Patent 533,369; 20 Switzerland, March 31, 1921, Patents 98,529 and 99,749; Italy, March 30, 1921, Patent 197,257, and April 6, 1921, application 301/1369; Belgium, March 31, 1921, Patent 295,263, and April 5, 1921, Patent 295,526, 25 and of which the following is a specification.

This invention relates to lace braiding machines and more particularly to so called one thread lace braiding machines, comprising as many bobbin carriers as carrier drivers.

The invention relates further particularly to such machines whose drivers are each rotatable clockwise and counter-clockwise.

One feature of the invention consists therein that the race plate having intersecting race openings arranged on a curve shows for each opening a member leaving race way portions between itself and the plate and apart from these members rotatable and arrestable carriers adapted to guide when arrested, the carriers past the outer and inner points formed in the race way plate by the said intersecting race openings.

Another feature of the invention consists in arranging the drivers at equal levels in such a way that the moving drivers can pass stationary neighboring drivers. This is accomplished by providing the carriers with driven parts that are of such thickness that the guiding parts of the stationary drivers guide the carriers past the pointed sections of the track even though the guiding portions of the drivers recede from the track.

Another feature consists therein that from the rack wheels adapted to rotate the drivers each clockwise and counter-clockwise the rack wheel nearest to the driver and surrounding the driver shaft is arranged on a sleeve also surrounding the driver shaft and stationarily arranged in the machine.

Still another feature consists in limiting the motion of the coupling means in such a manner that the springs tending to return the coupling means against the pull of a jacquard apparatus are not able to move the coupling means beyond a certain rest position.

A constructional form of the invention is illustrated in the drawing,

Fig. 1 being a plan view of a track plate with the bottom drivers beneath it,

Fig. 2 is a section on the line A—B of Fig. 1,

Fig. 3 an elevation of two adjacent operating devices for the drivers looking in the direction of the arrow in Fig. 2, the external parts of the one driving device being broken away.

Fig. 4 is a perspective view of a part of the track plate with the drivers beneath it.

Referring to the drawing a^1, a^2, a^3, a^4 represent four successive drivers whose axis are intersected by a circle b^1 . These drivers are arranged at equal heights as will be seen in Fig. 3. The shape of the drivers is such that the rotating drivers a^2, a^4 can move past the stationary drivers a^1, a^3 without striking against their edges. The points d of the outer edge of the track are further away from the circle b^1 than the points e of the inner edge of the track. The result obtained by this arrangement is that, even though the drivers are arranged in a curve or circle b^1 so that the outer sections of the symmetrical drivers a^1, a^3 are further apart than their inner sections, the drivers will nevertheless

guide the carriers past the points of the pointed sections of the track in a proper manner with the aid of disks f attached to the foot end of the carriers c . It will be seen from Fig. 1 that the distance x between the inner portions of the drivers a^1 , and a^3 is shorter than the distance y between the outer portions of the same drivers. The guide members j are disposed on a different circle b^2 from that of the drivers.

The starting and stopping of the drivers is accomplished in the following manner:

When a rod operated by a jacquard apparatus is pulled in the direction of one of the arrows shown in Fig. 2 the rod *g* is either raised or lowered. When the rod *g* is lowered the teeth of the coupling member *h* are thrown into engagement with the clutch of the toothed wheel *i*. The coupling member *h* is arranged to move up and down but not to rotate on the sleeve *k*. Assuming that the toothed wheel *i* rotates clockwise, the driver *a*³ will be moved clockwise by the sleeve *k* when the coupling member *h* is thrown into gear with toothed wheel *i*. A disk *l* is mounted on the sleeve *k* so as to rotate with it. The disk *l* has notches *m* into which a detent *n*, which may be rigidly fixed to the coupling fork *o*, at times protrudes. When the rod *g* is moved the detent *n* leaves the notches and wipes over the top or bottom surface of the disk *l*. The upward movement of the rod *g* compresses a spring *p* and another spring *q* mounted on the rod opposite the said spring remains inactive. The retrograde movement of the rod in either direction is controlled by means of pins *r* fixed to bars *s* and cross members *t* strike against the pins thus positioning the coupling fork and its detent in a predetermined position preferably at the central portion of the rod. When the jacquard apparatus ceases to operate the coupling member is maintained in engagement with the particular clutch until the detent *n* appears above or below a notch *m* in the disk *l* thereby snapping into engagement with the notch by the expansion of one of the springs hence the coupling member will be thrown out of gear and the disk *l* leaves the driver *a*³, in its stationary position in which it acts as a guide member. The toothed wheel *u* turns to the left while the toothed wheel *i* turns to the right, so that when the rod *g* is pulled down causing the coupling member *h* to engage with *u* the driver *a*³ will be rotated to the left.

The toothed wheel *i* is journalled on a fixed sleeve or hollow shaft *v* in order to prevent the driver from being caused to execute undesired rotary motion by the constantly rotating toothed wheel *i*. The toothed wheel *i* may be supported by a supporting member *w* which may be semi-circular in shape and attached to upright *z*.

The drivers may also be enabled to pass each other by some or all of them being arranged in different levels. In such cases the drivers may be made broader and the disk *f* may be dispensed with. But in accordance with the invention the points of the pointed sections of the outer edge of the bobbin track will then also have to be further from the circle *b*¹ than the points of the inner edge of the said track.

I claim:—

1. In a lace braiding machine, bobbin carriers, a race way plate having intersecting race openings arranged on a curve and forming inner and outer track points, for each said opening a member leaving race way portions between itself and the said plate, the said carriers being adapted to be guided in the said race way portions, and rotatable and arrestable carrier drivers also arranged on a curve, each of said drivers being associated to a said opening and adapted to be arrested in at least two positions and to guide in each of its arrested positions a said carrier past a said track point.

2. In a lace braiding machine, bobbin carriers, a race way plate having intersecting race openings arranged on a curve and forming inner and outer track points, for each said opening a member leaving race way portions between itself and the said plate, the said carriers being adapted to be guided in the said race way portions, and rotatable and arrestable carrier drivers also arranged on a curve, each of said drivers being associated to a said opening and adapted to guide a said carrier past a said track point, the outer points being arranged at a greater distance from the curve on which the said drivers are arranged than the inner track points.

3. In a lace braiding machine, bobbin carriers, a race way plate having intersecting race openings arranged on a curve and forming inner and outer track points, for each said opening a member leaving race way portions between itself and the said plate, the said carriers being adapted to be guided in the said race way portions, and rotatable and arrestable carrier drivers also arranged on a curve, each of said drivers being associated to a said opening and adapted to be arrested in at least two positions and to guide in each of its arrested positions a said carrier in the space between and past a said inner or outer track point until the said carrier has reached a said raceway portion and the said outer track points being arranged at a greater distance from the curve on which the said drivers are arranged than the inner track points.

4. In a lace braiding machine, bobbin carriers, a raceway plate having intersecting race openings arranged on a circle and forming inner and outer track points, for each said opening a member leaving raceway portions between itself and the said plate, the said carriers being adapted to be guided in the said raceway portions, and for each said opening a rotatable and arrestable carrier driver adapted to be arrested in two positions and to guide when arrested the carriers in the space between and past the said inner and outer track points until the

said carriers have arrived at said raceway portion.

5. In a lace braiding machine, bobbin carriers, a raceway plate having intersecting race openings arranged on a first circle and forming inner and outer track points, for each said opening a member leaving raceway portions between itself and the said plate, the said carriers being adapted to be guided in the said raceway portions, and for each said opening a rotatable and arrestable carrier driver also arranged on a second circle, adapted to be arrested in two positions and to guide when arrested the carriers in the space between and past the said inner and outer track points until the said carriers have arrived at said raceway portion, the outer track points being arranged at a greater distance from the second circle than the inner track points.

6. In a lace braiding machine, bobbin carriers, a raceway plate having intersecting race openings arranged on a circle and forming inner and outer track points, for each said opening a member leaving raceway portions between itself and the said plate, the said carriers being adapted to be guided in the said raceway portions, and for each said opening a rotatable and arrestable carrier driver adapted to rotate clockwise and counterclockwise, to be arrested in two positions and to guide when arrested the carriers in the space between and past the said inner and outer track points until the said carriers have arrived at said raceway portion.

7. In a lace braiding machine, rotatable and arrestable drivers each adapted to be rotated clockwise and counterclockwise, two driving wheels for each driver rotating in opposite directions, a coupling member adapted to be moved in opposite directions into engagement with the said driving wheels, a first means adapted to rotate with a driver, and a second means movable together with the said coupling member cooperating with the said first means so as to keep the coupling member and a driving wheel in engagement until the driver is to be arrested.

8. In a lace braiding machine, rotatable and arrestable drivers each adapted to be rotated clockwise and counterclockwise, two driving wheels for each driver rotating in opposite directions, a coupling member adapted to be moved in opposite directions into engagement with the said driving wheels, a disk adapted to rotate with the driver, and another member movable together with the said coupling member adapted to cooperate with the said disk so as to keep the coupling member and a driving wheel in engagement until the driver is to be arrested.

9. In a lace braiding machine, bobbin car-

riers, a raceway plate having intersecting race openings arranged on a curve and forming inner and outer track points and for each said opening a member leaving raceway portions between itself and the said plate, the said carriers being adapted to be guided in the said raceway portions, and for each said opening a rotatable and arrestable carrier driver having concavities adapted to guide the said carriers past the said points when the driver is arrested.

10. In a lace braiding machine the combination with driving plates each attached to a shaft each adapted to be rotated clockwise and counterclockwise, of two driving wheels arranged in different planes one being nearer the driving plates than the other and associated with said shaft, coupling means for coupling either of the said wheels with a said driving plate, and a stationary sleeve surrounding the said shaft and surrounded by the wheel nearest to the driving plates.

11. In a lace braiding machine the combination with driving plates each attached to a shaft each adapted to be rotated clockwise and counterclockwise, of two driving wheels arranged in different planes one being nearer the driving plates than the other and associated with said shaft, coupling means for coupling either of the said wheels with a said driving plate, a stationary sleeve surrounding the said shaft and surrounded by the wheel nearest to the driving plates, and an upright for supporting the said sleeve.

12. In a lace braiding machine the combination with driving plates each attached to a shaft each adapted to be rotated clockwise and counterclockwise, of two driving wheels arranged in different planes one being nearer the driving plates than the other and associated with said shaft, coupling means for coupling either of the said wheels with a said driving plate, a stationary sleeve surrounding the said shaft and surrounded by the wheel nearest to the driving plates, and a support for holding the driving wheel nearest to the driving plates.

13. In a lace braiding machine the combination with driving plates each attached to a shaft each adapted to be rotated clockwise and counterclockwise, of two driving wheels arranged in different planes one being nearer the driving plates than the other and associated with said shaft, coupling means for coupling either of the said wheels with a said driving plate, a stationary sleeve surrounding the said shaft and surrounded by the wheel nearest the driving plates, a support for holding the driving wheel nearest to the driving plates, and an upright for the said sleeve and support.

14. In a lace braiding machine, bobbin carriers with a projecting disk, a raceway

- plate having intersecting race openings forming inner and outer track points and for each said opening a member leaving raceway portions between itself and the said plate, the said carriers being adapted to be guided in the said raceway portions, and for each opening a rotatable and arrestable carrier driver having concavities adapted to guide the said carriers past the said points by means of the said projecting disks, when the driver is arrested.
15. In a lace braiding machine, bobbin carriers each with a projecting disk, a race-way plate having intersecting race openings forming inner and outer track points and for each said opening a member leaving raceway portions between itself and the said plate, the said carriers being adapted to be guided in the said raceway portions, and for each opening a rotatable and arrestable carrier driver having concavities adapted to guide the said carriers past the said points by means of the said projecting disk, when the driver is arrested, whereby the drivers 20 are arranged in the same plane and the concavities are so shaped that a rotating driver is adapted to pass an arrested driver in the same plane.
25. In a lace braiding machine, drivers, each adapted to rotate clockwise and counterclockwise, a disk having a recess and being adapted to rotate with a said driver, two wheels adapted to rotate in different directions, a coupling member, adapted to be moved in two directions to couple selectively the said driver with said wheels,

and an arresting means adapted to enter into the said recess, so as to arrest positively the said driver when the said coupling member is uncoupled.

40
17. In a lace braiding machine, drivers each rotatable clockwise and counterclockwise, a coupling member adapted to be moved from a middle position in opposite directions by means of a pull, springs tending to hold the coupling member in its middle position in opposition to the said pull, and stops for preventing the springs to act on the said coupling member beyond the said middle position.

45
18. In a lace braiding machine, bobbin carriers, a race way plate having intersecting race openings arranged on a curve and forming inner and outer track points, for each said opening a member leaving race way portions between itself and the said plate, the said carriers being adapted to be guided in the said race way portions, and rotatable and arrestable carrier drivers also arranged on a curve, each of said drivers being associated to a said opening and each adapted to rotate clockwise and counterclockwise and to be arrested in at least two positions and to guide in each of its arrested positions a said carrier past a said 50 track point.

55
In testimony whereof I have affixed my signature in presence of two witnesses.
